UNITED STATES PATENT OFFICE

HUGO E. ROSENKRANZ, OF OSHKOSH, WISCONSIN

CASKET LOWERING APPARATUS

Application filed January 22, 1929. Serial No. 334,214.

The object of my said invention is the provision of a casket lowering apparatus which is strong in construction and dependable in action, the latter being due to the friction 5 to which the working parts of the apparatus are subject incident to the lowering of a casket and which friction is at all times in proportion to the weight of the casket being lowered.

10 To the attainment of the foregoing the invention consists in the improvement as hereinafter described and definitely claimed.

In the accompanying drawings, forming part of this specification:

15 Figure 1 is a plan view of the apparatus constituting the preferred embodiment of the invention, in use.

Figure 2 is a side elevation, and Figure 3 an end elevation of the same.

20 Figure 4 is a broken vertical section, on an enlarged scale, illustrative of one end of the apparatus—i. e., the end at the right in Figures 1 and 2.

Figure 5 is a section on line 5—5 of Figure 25 4 and showing a portion of one side of the apparatus.

Figure 6 is a vertical section on the line 6—6 of Figure 1, looking in the direction indicated by arrow.

25 Figure 7 is an enlarged detail view of a portion of one of the longitudinal parallel side shafts to which the casket supporting straps are connected and on which said straps are wound.

Figure 8 is an enlarged detail view, partly in elevation and partly in section, showing the upright worm of the apparatus and certain elements associated therewith.

30 Figure 9 is an enlarged detail horizontal section taken in the plane indicated by the line 9—9 of Figure 4 and showing an important feature of the invention hereinafter explicitly referred to.

Figure 10 is a detail sectional view of one 45 of the end shafts of the apparatus—i. e., the end at the right of Figures 1 and 2.

Figure 11 is a transverse enlarged section on line 11—11 of Figure 10.

50 Figure 12 is a view on a large scale of the hand locking and unlocking device used in

conjunction with the apparatus as herein-after described.

Figure 13 is a view of a modification hereinafter explicitly referred to.

Similar numerals of reference designate 55 corresponding parts in all of the views of the drawings.

A burial casket 1 is shown in Figures 2 and 3 as being lowered in a grave 2, through the medium of strong straps 3 in loops on which 60 the casket rests as shown.

The ends of the said straps 3 are connected to longitudinal, parallel shafts 4 and are designed to be wound on said shafts and to be let off the same. One of said connections is 65 shown in Figure 7 and designated by 5, and said figure also shows the winding of a strap 3 on its shaft 4.

Each of the shafts 4 is tubular and has apertures 7 in its wall. End tubular sections 70 8 are telescopically arranged in the shafts 4 and are equipped with fastening studs 9 on U-shaped spring strips 10; the said spring strips being connected to the inner sides of the walls of the sections 8, and the studs extending through apertures in the sections 8 and into apertures 7 of the shafts 4 for the fastening of the shafts 4 and sections 8 together. Manifestly the provision of apertures 7 in each end portion of the shafts 4 permits of the sides or longitudinal portions being increased or diminished in length as occasion demands.

The connections 5 for the ends of the straps 3, Figure 7, to the tubular shafts 4 are 85 arranged in bights at the ends of the straps, and each of said connections 5 has an angular portion 11 at one end engaged with its shaft 4 in and adjacent to an aperture 12 in the shaft wall while its opposite end is provided with an angularly-disposed toe 13 removably arranged in an aperture 14 in the shaft wall. By virtue of this construction the straps 3 may be readily connected to and disconnected from the shafts 4 when desired, and yet there is no liability of any strap end being casually disconnected from its shaft 4 while the apparatus is in operation.

In addition to the elements thus far specifically referred to, the apparatus comprises 100

four corner casings 15, 16, 17 and 18 relatively arranged as shown in Figures 1-3. The tubular shaft sections 8 adjacent to the casings 15 and 16, Figures 1 and 6, are connected at 19 to flanged sleeves 20 turnable in walls of said casings 15 and 16 and secured thereto by collars 21, Figure 6.

The connections just described constitute swivel connections calculated to enable the corner casings to accommodate themselves to inequalities of the ground adjacent to a grave.

Interposed between and connecting the casings 15 and 16 together is a connector made up of an intermediate tubular section 22 and end tubular sections 23 adjustably connected to the section 22 and connected to the casings 15 and 16 after the manner shown in Figure 6 at 24 or in any other approved manner. For the sake of clearness I would say that the section 22 is adjustably connected with the sections 23 in the same manner that the before-mentioned shafts 4 are connected to the sections 8; also, that the adjustable connection of the sections 22 and 23 is resorted to in order that the width of the apparatus may be increased and diminished as occasion demands.

One of the shaft sections 8 is journaled in and appropriately held against endwise movement relative to the casing 17, and fixed on said shaft section 8 and arranged in casing 17 is a spur gear 24, intermeshed with a spur gear 25 fixed to a worm gear 26 that is meshed with a worm 27.

The connection intermediate of the casings 17 and 18, Figures 1, 10 and 11, comprises a tubular intermediate section 28 and tubular sections 29 telescopically arranged in the section 28 and adjustably connected thereto, Figure 10, through the medium of buttons 30 carried by spring strips 31 attached to the sections 29 and adapted to extend through apertures in said sections 29 and into apertures 32 of the section 28.

Turnable in the section 28 is a head 33, and connected at 34 to said head and extending in opposite directions therefrom are tubular shafts 35 of angular cross-section, Figures 10 and 11.

Telescopically arranged in the shafts 35 are shafts 36 and 37, Figures 4, 10 and 11, of corresponding cross-section. The shaft 36 is connected at 38, Figure 4, to the before-mentioned worm 27 in casing 17, and the shaft 37 is connected at 38^x to a worm 39 mounted in the casing 18.

The side section 8 adjacent to the casing 18 is connected at 40, Figure 5, to a flanged sleeve 41 journaled in the casing 18 and fixed to a spur gear 42 disposed within the casing. Said gear 42 is meshed with a gear 43 fixed on a shaft 44, and also fixed on said shaft 44 is a worm gear 45 meshed with the worm 39. Fixed to the worm 39 is a worm gear 46,

Figure 5, and meshed with said worm gear 46 is an upright worm 47, Figures 4, 5 and 8. The shaft 48 of the worm 47 is journaled in the casing 18 and is flanged at 49 for the pivotal connection at 50 of horizontally swingable members 51, equipped at 52 with appropriate friction-creating material and disposed in a cylindrical member 53 fixed in the casing 18. In the event of the worm 47 tending to turn too fast incident to the gravitational descent of a casket that is being lowered through the medium of the apparatus, the members 51 by exerting pressure against the casing 53 will frictionally hold back the worm 47 and retard the descent of the casket as is desirable.

Rotation of the worm 47 and downward movement of a casket are prevented in the first instance by the action of a sleeve 54 against a friction pad or felt disk 55; said sleeve being threaded in the casing 18, Figure 8, and being equipped with a toothed disk 56. When, however, the sleeve 54 is moved upwardly through the medium of a tool 57, Figure 12, applied thereto, the friction will be gradually lessened and the worm 47 will be gradually released and permitted to turn under the weight of the casket for the steady and slow lowering of the latter.

In addition to the friction pad 55 and the friction pads 52 I prefer to employ three friction pads 58, 59 and 60; the pad 58 being between a flange 61 and the shaft of worm 27 and a portion of the casing 17, the pad 59 being between a flange 62 on the shaft of the worm 39 and a portion of the casing 18 and the pad 60 being between the bottom of the cylinder 53 and the lower flange 49 of the worm 47.

It follows from the foregoing that the casket being lowered is subject during the lowering operation to friction, and is at all times incident to the lowering checked by one or more of the pads; also, the greater the weight of the casket the greater will be the friction created by the action of the pads, due to the fact that said weight automatically causes the various worms and gears to push upward and outward against their respective friction surfaces.

It will further be noted that in my improvement means for creating friction are present adjacent the lower end and the upper end of the main worm 47, and that all of the worms are, in action, thrust against pads with the result that the friction is increased in proportion to the weight or pull on the straps of the casket that is being lowered.

By virtue of the construction shown in Figures 10 and 11 provision is made for extension or retraction of the means connecting the casings 17 and 18 for adjustment purposes and yet a positive and strong connection is afforded between the worms 39 and 27 for

assuring synchronous checking and turning of the side shafts 4 of the apparatus.

The connections disclosed between the casings, on the one hand, and the side means intermediate of the casings, on the other, are materially advantageous inasmuch as they enable the casings 15-18 to accommodate themselves to inequalities of the ground adjacent to the four corners of a grave and in that way conduce to proper operation of the apparatus.

In Figure 13 I show the shaft 48 of worm 47 equipped with a disk 48^w for cooperation with a foot lever 49^w, fulcrumed in the adjacent casing. This construction can be used either at the top or at the bottom of the worm and constitutes a brake attachment. When deemed expedient the said disk may, within the purview of my invention, be attached to the rod which connects the two geared casings.

Figure 9 makes clear adjustment means for the swingable members 51. The extra holes in members 51 are advantageous because by placing the pins 50 in different holes of the members 51 the friction may be increased or diminished, as is desirable.

I have entered into a detailed description of the preferred embodiment of my invention in order to clearly disclose said embodiment. I do not desire, however, to be understood as limiting myself to the construction and relative arrangement of the elements as shown and described, my invention being defined by my appended claims within the scope of which modifications may be made without departure from my invention.

Having described my invention, what I claim and desire to secure by Letters Patent, is:

1. The combination with a casket lowering apparatus including casket suspending straps, side shafts turnable to let said straps off the same, and corner casings in which said shafts are turnable, of means for checking the turning of said shafts under the gravitational action of a casket, said means including meshed worms and worm gears, the worms having smooth portions, in two of said casings and positively connected together and with said side shafts, and friction creating means enclosed in two of the casings and arranged to cooperate with the smooth portions of the worms therein.

2. The combination with a casket lowering apparatus including casket suspending straps, side shafts turnable to let said straps off the same, and corner casings in swivel connection with said side shafts, and connectors between said casings, of means for checking the turning of said shafts under the gravitational action of a casket, said means including meshed worms and worm gears, the worms having smooth portions, in two of said casings, and positively connected

together with said side shafts, and friction creating pads associated with two of the casings and the worms therein and subject to endwise thrust of the worms, and friction creating means enclosed in one casing and about a smooth portion of one worm and adapted to restrain rotation of said worm.

In testimony whereof I affix my signature.

HUGO E. ROSENKRANZ.
